UNITED STATES PATENT OFFICE

DAVID J. BILLER, OF ST. LOUIS, MISSOURI, ASSIGNOR TO DAY-BRITE REFLECTOR COMPANY, OF ST. LOUIS, MISSOURI, A CORPORATION OF MISSOURI

ELECTRIC-LIGHTING FIXTURE

Application filed August 20, 1927. Serial No. 214,254.

My invention relates to electric lighting fixtures and systems for display cases and the like, particularly to fixtures adapted to be placed on the outside of a case, such as 5 refrigerator cases for displaying perishable articles.

The invention has for its principal objects a simple and neat mounting of a series of fixtures along the display case, and an individual fixture that is simple in construction and is provided with means for protecting against overheating the outer shell which may come in contact with a person inspecting the contents of the case. The 10 invention consists principally in mounting concealed wiring in a passageway extending through the frame member of the showcase, mounting metal housings in transverse openings communicating with said longitudinal passageway and securing a fixture at each housing in position to conceal it and said transverse passageway, the wiring for said fixture extending through said transverse passageway into the fixture between the inner and outer shells thereof, so that 15 no portion of the wiring is exposed to view. The invention also consists in an individual fixture comprising a perforated outer shell and an inner shell or reflector member having a marginal flanged portion secured to 20 said frame member of the case and contacting with one of said housings, and also having a rebent marginal flanged portion secured to the edge of the outer shell member, the reflector member being otherwise entirely clear of said outer shell member. The 25 invention further consists in the illuminating fixture and system and in the parts and combinations and arrangements of parts 30 hereinafter described and claimed.

In the accompanying drawings,

Fig. 1 is a fragmentary elevation of a refrigerator display case and an electric lighting system and fixtures embodying my 35 invention,

Fig. 2 is an enlarged top plan view,

Fig. 3 is an enlarged elevation with portions of each fixture broken away,

Fig. 4 is a sectional view on the line 4-4 40 in Fig. 3,

Fig. 5 is a sectional view on the line 5-5 in Fig. 3,

Fig. 6 is a sectional view on the line 6-6 in Fig. 5, and

Fig. 7 is a sectional view on the line 7-7 45 of Fig. 6.

It is obviously advantageous to locate the electric illuminating fixtures of refrigerator cases and the like outside the case, so as to avoid heating the interior of the case. 50 However, such exterior illuminating devices frequently become overheated and may cause discomfort or even injury if touched by persons inspecting the contents of the case and they are frequently very unsightly. 55 The present invention seeks to avoid the risk of overheating the fixtures and to overcome the other disadvantages of other exterior illuminating devices

The drawing illustrates the upper front 70 edge portion of a refrigerator showcase, comprising a longitudinal frame member 1, a pair of spaced top glass plates 2 and three spaced front glass plates 3. The frame member 1 has a longitudinal passageway 4 75 extending therethrough, said passageway being concealed from view. At intervals, transverse passageways 5 open into said longitudinal passageway 4 and extend to the front outer edge of the longitudinal frame 80 member. In each transverse passageway 5 is extended a metal housing 6.

Secured to the frame member 1 at each transverse passageway is an electric illuminating fixture indicated generally by the 85 numeral 7. The inner shell or reflector member 8 of each fixture has a transversely bowed body to one end of which is secured a socket member 9 for an electric light 10, an elongated electric bulb of the kind commonly 90 used in illuminating display cases being indicated in the drawing.

Said reflector member 8 has a flanged portion 11 that contacts flatwise with a mounting strip 13^a, the two being secured to the 95 frame member 1 on either side of a transverse passageway as by screws 12. Said mounting strip 13^a has a rebent marginal flange 13 to which is secured an outer shell member 14 of transverse curvature. Said 100

- outer shell member 14 is large enough to be entirely clear of the reflector member 8 except along the marginal portion that is secured to the flange 13 of the mounting strip 13^a of the reflector member. Preferably the outer shell is provided with slots 15 enlarged at one end to receive headed screws or pins 16 secured to the rebent flange 13 of the reflector member so that the outer shell may be easily removed from said reflector member.
- 5 A flexible metal tube 17 containing the main electric feed wires 18 for the group of fixtures 7 extends through said longitudinal passageway 4 in the frame member of the case. At each transverse passageway, wires 19 branch off from the main wires to serve the individual fixture 7. Said wires 19 extend through a hole 20 provided therefor in the flange portion 11 of the reflector member and 10 are thus concealed between the reflector member 8 and the outer shell member 14. The housings are suitably grounded as through the metal tube 17 in which the main feed wires 18 are mounted and the flanged portion 11 of the reflector member contacts with said housing 6; so that in case of a short circuit or any electric trouble, the fixture 7 will be grounded, thus avoiding the risk of giving an electric shock to any person touching the outer shell 14 or the reflector member 8. The outer shell is provided with ventilating openings 21 to permit escape of heated air from the space between the reflector and the outer shell.
- 15 The above described illuminating fixture and system for refrigerator display cases have numerous advantages. The entire system and the individual fixtures are simple in construction and easy to assemble and disassemble. The wiring is concealed and the individual fixtures present a very neat external appearance. Obviously numerous changes may be made without departing from the invention and I do not wish to be limited to 20 the precise construction shown.
- 45 What I claim is:
1. An electric lighting fixture for display cases and the like having a longitudinal frame member, comprising a reflector member having a flanged marginal portion secured to said frame member and an outer shell supported entirely by means securing it to said reflector member along one edge, said outer shell being otherwise clear of said reflector member and spaced away therefrom.
  2. An electric lighting fixture for display cases and the like having a longitudinal frame member, comprising a reflector member having a flanged marginal portion secured to said frame member and an outer shell supported entirely by means securing it to said reflector member along one edge, said outer shell being otherwise clear of said reflector member and spaced away therefrom.
  3. An electric illuminating system for display cases and the like comprising a longitudinal frame member of said case provided with a concealed longitudinal passageway and lateral passageways opening into said longitudinal passageway, a flexible metal tube containing electric wiring extending through said longitudinal passageway, electric wiring connected thereto and extending through a metal housing provided therefor in each transverse passageway and a plurality of metal illuminating fixtures secured to said frame member and each concealing one of said transverse passageways, said electric wiring extending from said transverse passageways into said fixtures, said fixtures contacting with said housings and said housings with said tube, thereby grounding said fixtures.
  4. An electric lighting fixture for display cases and the like comprising a longitudinal frame member of said case through which extends a concealed longitudinal passageway and which is provided with a transverse passageway opening into said longitudinal passageway, a reflector member, an electric light socket member secured thereto, said reflector member having a flanged portion secured to said frame and concealing said transverse opening, an outer shell secured to said reflector member along one edge and being otherwise clear thereof and electric wiring extending through said longitudinal passageway, into said transverse passageway and through said flanged portion of said reflector member into the space between said reflector member and said outer shell.
  5. An electric lighting fixture for display cases and the like comprising a longitudinal frame member of said case through which extends a concealed longitudinal passageway and which is provided with a transverse passageway opening into said longitudinal passageway, a reflector member, an electric light socket member secured at one end thereof, said reflector member having a flanged portion secured to said frame and concealing said transverse opening, said reflector member also having a rebent marginal flange, an outer shell removably secured to said rebent marginal flange of said reflector member along one edge and being otherwise clear thereof and electric wiring for said light socket member extending through said longitudinal passageway, into said transverse passageway and through an opening provided therefor in said flanged portion of said reflector member into the space between said reflector member and said outer shell.
  6. An electric lighting fixture for display cases and the like having a longitudinal

- frame member, comprising a reflector member having a flanged portion and a separate flange member secured flatwise to said reflector member flange and to said frame member and having a rebent marginal flange and an outer shell secured to said rebent marginal flange along one edge, said outer shell being otherwise clear of said reflector member.
7. An electric lighting fixture for display cases and the like comprising a longitudinal frame member of said case through which extends a concealed longitudinal passageway and which is provided with a transverse passageway opening into said longitudinal passageway, a reflector member, an electric light socket member secured thereto, said reflector member having a flanged portion extending along said frame, a mounting strip contacting flatwise with said flanged portion of said reflector, screws passing through said strip and flange to secure them to said frame, thereby concealing said transverse opening, said strip having an outwardly extending flange, an outer shell secured to said flange along one edge and being otherwise clear of said reflector member and electric wiring extending through said longitudinal passageway, into said transverse passageway and through said flanged portion of said reflector member and said mounting strip into the space between said reflector member and said outer shell.
8. An electric lighting fixture for display cases and the like comprising a longitudinal frame member of said case through which extends a concealed longitudinal passageway and which is provided with a transverse passageway opening into said longitudinal passageway, a reflector member, an electric light socket member secured at one end thereof, said reflector member having a flanged portion extending along said frame, a mounting strip contacting flatwise with said flanged portion of said reflector member, screws passing through said strip and flange to secure them to said frame member, thereby concealing said transverse opening, said mounting strip having a flange, an outer shell removably secured to said flange along one edge and being otherwise clear of said reflector member and electric wiring for said light socket member extending through said longitudinal passageway, into said transverse passageway and through openings provided therefor in said flanged portion of said reflector member and in said mounting strip into the space between said reflector member and said outer shell.

Signed at St. Louis, Missouri, this 18th day of August, 1927.

DAVID J. BILLER.
